No. 741,410.

PATENTED OCT. 13, 1903.

W. PLATT.

DOOR STOP.

APPLICATION FILED JULY 28, 1903.

NO MODEL.

Fig. 1.

UNITED STATES PATENT OFFICE.

WILLIAM PLATT, OF ALLEGHENY, PENNSYLVANIA.

DOOR-STOP.

SPECIFICATION forming part of Letters Patent No. 741,410, dated October 13, 1903.

Application filed July 28, 1903. Serial No. 167,266. (No model.)

To all whom it may concern:

Be it known that I, WILLIAM PLATT, a citizen of the United States of America, residing at Allegheny, in the county of Allegheny and State of Pennsylvania, have invented certain new and useful Improvements in Door-Stops, of which the following is a specification, reference being had therein to the accompanying drawings.

This invention relates to certain new and useful improvements in door-stops; and the object of the invention is to construct a simple, cheap, and effective device of this type and comprising a box or casing in which is located a pair of spring-pressed jaws adapted to receive a head carried on a stop which is attached to the door. Means is provided for forcing the jaws downwardly to disengage the same from the stop carried by the door, whereby the latter can be closed. Means is provided in the case for normally forcing the jaws upwardly whereby to be in position to engage with the stop carried by the door. The stop carried by the door is preferably provided with a buffer or cushion in order that this stop may be employed as the ordinary cushion-stop, if desired.

All the above construction will be herein-after more fully described, and specifically pointed out in the claims, and in describing the invention in detail reference is had to the accompanying drawings, forming a part of this specification, and wherein like numerals of reference indicate like parts throughout the several views, in which—

Figure 1 is a perspective view of a part of a room and door, showing the application of my improved door stop or check. Fig. 2 is a central vertical sectional view showing the stop detached from the lug and in locked engagement with the spring-pressed jaws. Fig. 3 is a detached detail perspective view of the spring-pressed jaws, showing a part of the plunger and casing carrying the jaws. Fig. 4 is a horizontal sectional view of the casing, showing the spring-pressed jaws in top plan.

To put my invention into practice, I provide a casing, shell, or housing 1, provided at its base with outwardly-extending lugs 2, through which may be passed fastening screws or nails for securing the casing firmly in position upon the floor. The casing is situated

on the floor, usually adjacent to the wall, so that when the door is opened the stop carried thereby will engage with the mechanism in 55 the casing and hold the door in the open position. The casing is provided in its front wall with an opening 3, and fitted to slide vertically in the casing or shell 1 is a box or frame 4, to which is attached a yoke 5, having 60 a plunger 6 connected to its upper end. This plunger 6 extends through the top plate 7 of the casing and is provided on its upper end with a suitable knob or head 8. The plate 7 may be advantageously secured to the casing 65 1 by providing outwardly-extending lugs at the ends of the top plate and providing similar lugs on the casing to receive securing screws or bolts. The boxing or frame 4 consists of a bottom plate with two rectangular 70 boxes or casings 9 secured thereon and each of which is provided on its inner face, near the forward end, with an opening through which project the jaws 10, which are held normally projected through the openings by 75 the tension of springs 11, which bear against the rear ends of said jaws and are fastened to the inner wall of the boxings 9. The front faces of these jaws 10 are beveled, whereby to permit the jaws being forced inwardly into 80 their boxes when the stop carried by the door engages therewith.

The stop or catch carried by the door comprises a shank 12, provided with a substantially spear-shaped head 14, the shank at its 85 other end having apertured lugs 15 to receive means for securing the catch to the door 16. Interposed between the rear end of the stop or catch and the door 16 is a buffer 17, of rubber or other like material, whereby 90 the catch can be used as an ordinary stop for engagement with the wall. The spring-pressed jaws 10 are normally held in position to receive and engage the spear-shaped head 14 of the stop by means of a spring 18, arranged on the guide-pin 19, which is mounted in the base of the box and extends through the guide-opening 20, provided therefor in the bottom of the box or frame. When the door is open and the spear-shaped head 14 engages spring-pressed jaws 10, the latter are forced apart until the head 14 passes them, at which time the springs force the edges of the jaws into engagement with the notches 100

21 of the head, whereby to hold the door in the open position.

When it is desired to close the door, the spring-pressed jaws and their box or frame are depressed, which may be done by foot-pressure on top of the head or knob 8, causing the plunger to depress the jaws and their frame, moving said jaws out of engagement with notches 21, allowing the door to be free 10 to be closed. When the stop or catch moves out through opening 3 and pressure on the plunger is relieved, the spring 18 elevates the plunger and spring-pressed jaws to their normal position, so that said jaws are again 15 in front of opening 3 to receive the catch when the door would again open.

In the practice of the invention it will be obvious that slight changes may be made in the details of construction without departing 20 from the general spirit of my invention.

Having fully described my invention, what I claim as new, and desire to secure by Letters Patent, is—

1. A door-stop comprising in combination 25 with a catch secured to the door and provided with a spear-shaped head, a casing adapted to be secured to the floor and provided in its front wall with an opening, a boxing or frame arranged to slide vertically in the casing, a 30 spring arranged underneath said boxing or frame and exerting its pressure upward

against the same, spring-pressed gripping-jaws carried by said boxing or frame to engage with the spear-shaped head of the catch carried by the door, a yoke secured to the 35 boxing or frame, and a plunger connected to said yoke and extending through the top of the casing, substantially as described.

2. In a device of the character described, the combination with a stop or catch secured 40 to a door and provided with notches, and a buffer or cushion between the stop or catch and the door, of a casing adapted to be secured to the floor and provided in its front wall with an opening, a boxing or frame with- 45 in the casing and adapted to be moved vertically therein, spring-pressed jaws carried by said boxing or frame to engage with the notches in the stop or catch carried by the door, means underneath the boxing or frame 50 to hold said jaws normally in position to receive the stop or catch, and a plunger connected to the boxing or frame and extending through the top of the casing, as and for the purpose described.

In testimony whereof I affix my signature in the presence of two witnesses.

WILLIAM PLATT.
